UNITED STATES PATENT OFFICE.

LIBORIO E. RIVAS, OF SANTA RITA, NEW MEXICO.

KEY HOLDER.

Application filed September 29, 1927. Serial No. 222,776.

This invention relates to key holders.

An object of this invention is to provide a key holder suitable for attachment either to a belt or pocket, and adapted to carry a key ring without flapping of the chain and yet to provide for a long chain when it is desired to use the keys.

A further object of this invention is to provide a key holder of simplified form, convenient for carrying about, which occupies a minimum space, which is quickly and easily attached and detached, which may be manufactured at low cost, and which is strong and durable.

15 With the foregoing and other objects in view, I have invented the device shown in the accompanying drawings, in which:

Figure 1 is a front elevation of my device. Figure 2 is a side elevation.

20 Figure 3 is a modification.

Figure 4 is another modification.

Like reference characters indicate like parts throughout the several views, and in the specification, in which I provide a body member 2, provided with a pair of aligned eyelets 3, in the upper bifurcated portions of the body 2. The lower portion of the body is provided with sockets 4, in which sockets pivotally fit the terminals of a chain holder 5, carrying a chain 6, in the terminal of which chain 6 is a ring 7, for carrying the keys 8.

In operation, a belt such as 9, is passed through the eyelets 3, and when the keys 8 are not being used, the ring 7 is held by a snaphook 10. When it is desired to use the keys, they are released from the snaphook 10, which allows extension of the chain 6; whereas, when the ring 7 is held within the snaphook, the chain is folded back and out of the way. Thus a much longer chain

than usual may be had without tangling of the keys. The snaphook 10 comprises a bent terminal 11 and a spring 12, which spring 12 is anchored to the body 2.

In the modification shown in Figure 3, I provide, in place of the eyelets 3, a pair of clip terminals 3', which clip terminals fit over and clamp the edge of a pocket, or other desired anchoring place upon the clothing. In this form it is preferable to form the body 2 and the projecting portions therefrom from strong sheet metal.

Claims:

1. A key carrying device comprising a piece of sheet metal bifurcated at one end, the bifurcated portion bent to form clips, the other end bent to form a hook, a spring supported by the member for cooperating with the hook to form a snap hook, and a key chain carried by the member.

2. A key holder comprising a body, means on the body for engaging an article of apparel, a key chain of relatively great length having one end connected to an intermediate portion of the body, and a hook carried by the lower portion of the body for engaging the opposite end of the chain, when a key carried thereby is not in use.

3. A key holder comprising a body, apparel engaging loops carried by the upper end of the body, a socket carried by an intermediate portion of the body, a key chain of relatively great length having one end anchored to said socket, and a snap hook carried by the lower portion of the body for engaging the opposite end of the chain when a key carried by said chain is not in use.

In testimony whereof I affix my signature.

LIBORIO E. RIVAS.
